UNITED STATES PATENT OFFICE.

WILLIAM I. ELY, OF DETROIT, MICHIGAN.

MATCH-SPLINT MACHINE.

SPECIFICATION forming part of Letters Patent No. 291,314, dated January 1, 1884.

Application filed August 30, 1883. (No model.)

To all whom it may concern:

Be it known that I, WILLIAM I. ELY, of Detroit, county of Wayne, State of Michigan, have invented a new and useful Improvement 5 in Match-Splint Machines; and I declare the following to be a full, clear, and exact description of the same, such as will enable others skilled in the art to which it pertains to make and use it, reference being had to the accompanying drawings, which form a part of this 10 specification.

My invention consists of the combination of devices and appliances hereinafter specified, and more particularly pointed out in the 15 claims.

Figure 1 is a side elevation of a device embodying my invention. Fig. 2 is a plan view. Fig. 3 is a separate view of the mechanism for slicing the splints. Fig. 4 is a separate view 20 of the cross-cutting mechanism. Fig. 5 is an end view of the same. Fig. 6 is an end view of the mechanism for feeding the timber. Fig. 7 is a front view of the same.

The object of my invention is to provide an 25 improved machine for cutting match-splints.

I carry out my invention as follows:

A represents any suitable supporting-frame. B is the driving-pulley, mounted upon the shaft b, said shaft connected by a worm-gear, 30 C, with the shaft d of the driving-wheel D. This driving-wheel is provided with a suitable connecting-rod, D', by which it is attached to the sliding bed E in any suitable manner. It is evident that this mechanism already described is adapted to reciprocate said bed upon 35 suitable ways, e, upon the frame. I would have it clearly understood, however, that I do not limit myself to this precise mechanism for reciprocating said bed upon its ways, as 40 the bed may be reciprocated by any suitable mechanism, said mechanism coming within the scope of my invention.

F is an arbor, carrying a series of saws or other suitable cutters, f.

G is a belt connected with said arbor, and with the shafts b by which said arbor is driven.

f' represents a series of collars upon the arbor between the cutters, of any suitable 50 length, and by which the distance between the

cutters may be regulated for any desired length of splints.

H is an arm secured upon the frame, for supporting the arbor. Said arm H is provided with two or more pivoted levers, h and h', one or both of said levers provided with a weight, H'. The levers h and h' are provided with universal joints or bearings h² and h³, upon which the arbor is suspended, the construction being such that the arbor may always be held in a horizontal position, and consequently make a straight cut upon the timber. The two pivoted levers h and h' are connected by a bar, H', said bar preferably curved at one end, as shown, and adapted to be engaged by suitable shoulders, E, upon the bed-plate as the bed-plate is reciprocated, the construction being such that when said shoulder is engaged against said bar, as the bed is moved in the proper direction, the arbor will be brought down upon the pivoted levers h and h' to engage against the timber I to make its cut. As the bed-plate is reciprocated in the opposite direction the weight H' will elevate the arbor again, so that the timber may be carried forward from beneath the cutters upon the arbor and into contact with the cutter J, by which the splints are cut into suitable widths, said cutters J being driven by an additional belt, J', connected therewith, and with the shaft b. As the bed-plate continues to move forward by means of the stroke of the connecting-rod D', the timber is brought under the cutter K. Said cutter may be secured upon the frame in any desired manner— as, for instance, by means of a compound lever, L, pivoted to the frame. One end of the said compound lever projects inwardly, as shown at l. When the bed-plate is moved forward against said projecting end l, the cutter K is caused to give a shear cut upon the timber, thereby slicing or shaving off from the timber the splints already cut into suitable lengths and widths.

I do not confine myself to the precise method shown of hanging the cutter K, as it may be operated in any suitable manner. The compound lever L is also provided with a suitable weight, M, adapted to raise the cutter K after its cut has been given, and the bed-plate is

caused to reciprocate in the opposite direction. The timber may be worked up to the cutters upon the arbor in any suitable manner. I do not limit myself to any particular method of accomplishing this result. In Figs. 6 and 7, however, I show an adjustable rack-pawl, N , suitably secured to the bed. The end of the rack is provided with a retracting-spring, n .

10 O is an arm pivoted upon the bed, said arm provided with a cam, o, the width of which corresponds with the desired width of the match.

15 P is a stop secured upon the frame, the construction being such that as the bed is moved in the proper direction the cam o will be caused to engage against the end of the rack and project it, with the slide Q connected therewith, forward the same distance when 20 the bed is moved in the opposite direction, and the arm o moves away from the stop P, the retracting-spring n will force the rack backward, and the end of the pawl will drop forward and hold the slide Q in place. The 25 bed E may be provided with any suitable number of arms, O, said arms preferably connected together by a rod or bar, o, so as to be operated simultaneously. Any other suitable mechanism may be employed to feed the work 30 to the cutters without departing from the principle of my invention.

The operation of the device will be understood. The timber being secured upon the bed-plate is brought first under the cutters 35 upon the arbor F and sawed into widths corresponding with the desired length of the matches. The cut of the knives f upon the arbor may be regulated to any desired depth. As the bed is then moved forward by means 40 of the connecting-rod D', the timber next comes into contact with the cutter J, by which the splints are cut into the desired widths. Next it is carried forward beneath the cutter K, by which the splints are cut from the timber. It is evident that, the timber being already cut into blocks corresponding to the 45 length of the splints, the operation of the arbors with its cutters may be discontinued, and said blocks caused to pass by the cutter J and 50 under the cutter K. In this instance the cutters J and K are sufficient for the purpose desired. I therefore design to employ the cutters J and K with suitable operating mechanism, or by the cutting mechanisms described, 55 as may be needed.

It is evident that my invention consists, essentially, in providing mechanism for cutting the blocks, so as to form suitable lengths for the splints, then in cutting said blocks 60 into suitable widths for the splints, and then in shearing them off from the block, although the two latter operations may be performed, the first being omitted.

It will be seen that by providing a machine for the purpose described which combines mechanism for accomplishing the results

named all the operations required in the manufacture of match-splints may be readily accomplished thereby. Moreover, the construction shown and described does not compel any compression of the wood of which the match-splints are composed, as is shown in many devices of this class, which compression renders the wood less easily combustible than when left in its own density, as 75 will be the case in the use of this device.

What I claim is—

1. The combination, in a match-splint machine, of a bed for carrying the block to be cut, a rising and falling arbor, F, having cutters to form the block into lengths for the splints, a cutter, J, for cutting the block into suitable widths for the splints, a cutter, K, for shearing off the splints, and mechanism for operating all the cutters, substantially as 80 described.

2. In a match-splint machine, the combination of a reciprocating bed, E, for carrying the block to be cut, an arbor, F, having cutters for forming the block into lengths 90 for the splints, a cutter, J, for forming the block into suitable widths for the splints; a cutter, K, for shearing off the splints, and means for raising and lowering the arbor and operating all the cutters, substantially as 95 described.

3. The combination, with the cutters J and K, arranged one in advance of the other, and means for operating the cutters, of a bed, E, for carrying the block to be cut, and mechanism for reciprocating the bed to present the block first to the cutter J to form the width of match-splints, and subsequently to the cutter K for shearing off the splints, substantially as described.

4. The combination, in a match-splint machine, of an arbor, F, carrying cutters, devices for supporting the arbor and permitting it to rise and fall, a reciprocating bed for carrying the block, means for lowering and raising the arbor to cut the block into lengths for the splints, a cutter, J, for cutting the block into the width for the splints, and a cutter, K, for shearing off the splints, substantially as described.

5. In a match-splint machine, the combination of a sliding bed, E, and arbor, F, provided with a series of cutters, suspended levers h h' , supporting the arbor, a bar, H^2 , connecting said levers, a stop on the sliding bed, arranged to act on the bar connecting the levers to lower the arbor and bring the cutters into action on the material, and means for elevating the arbor away from the material, substantially as described.

6. The combination, in a match-splint machine, of the sliding bed and the cutters for forming the splints, with a slide, Q, on the bed, a rack, N , a retracting-spring, n , connected with the rack, an arm, O, having a cam, o, and a stationary stop, P, for acting on the arm and causing its cam to advance the

rack and slide to feed the material to the cutters, substantially as described.

7. In a match-splint machine, the combination of a work-carrying bed, an arbor having 5 a series of cutters to cut the material into lengths for the splints, cutters arranged to cut at right angles to those on the arbor, for cutting the material into widths for the splints, a cutter for shearing off the splints, and mech-

anism for operating all the cutters, substantially as described.

In testimony whereof I sign this specification in the presence of two witnesses.

WILLIAM I. ELY.
